UNITED STATES PATENT OFFICE.

ROBERT STODDARD, OF CHICAGO, ILLINOIS, ASSIGNOR TO MILK BOTTLE CRATE COMPANY, OF CHICAGO, ILLINOIS, A CORPORATION OF ILLINOIS.

BOX OR CRATE.

Application filed July 25, 1924. Serial No. 728,170.

To all whom it may concern:

Be it known that I, ROBERT STODDARD, a citizen of the United States, residing at Chicago, in the county of Cook and State of Illinois, have invented certain new and useful Improvements in Boxes or Crates, of which the following is a specification.

This invention relates to a novel and improved box or crate and more particularly to a novel and improved corner thereof and has for its object to provide a corner for boxes and crates which are subjected to rough usage and which will act as a protection therefor.

More specifically the object is to provide a novel and improved stacking iron which may be employed upon a box or crate, of a type which may be applied to boxes or crates of the kind which are usually stacked one on top of the other.

Other objects will become apparent as the description progresses.

In the accompanying drawings in which I have shown a preferred embodiment of my invention,

Fig. 1 is a perspective view of a corner of a box or crate with my invention applied thereto.

Fig. 2 is a plan view of the structure shown in Fig. 1.

Fig. 3 is a section on the line 3—3 of Fig. 2.

Fig. 4 is an elevation of my improved stacking iron and

Fig. 5 is a bottom plan view thereof.

Referring now to the drawings, 1 and 2 indicate sides of a box or crate forming a corner 3. It is common to provide reinforcements and stacking irons at the corners of boxes or crates of the type which are usually stacked one upon the other, such for example as milk bottle crates. These stacking irons have commonly consisted of flat members riveted or bolted, or even nailed to the top slat or board of the crate or box. The result is that they are soon torn off by the rough usage to which such boxes or crates are subjected. To provide against such mishaps I make my improved stacking iron and reinforcement preferably of one piece of material, such as sheet metal, and having the horizontal top 4, vertical sides 5 and 6 at right angles to each other and terminating in bent-in lugs 7 and 8.

The top 4 is provided with a struck-up pro-

jection having a horizontal top 9 and vertical sides 10 and 11 at right angles to each other.

In the sides 1 and 2 of the box I provide slots 12 and 13 extending perpendicularly to the faces of the sides and so placed as to receive the lugs 7 and 8. Preferably the vertical sides 5 and 6 and the horizontal top 4 are countersunk into the material of the box or crate so as to provide flush surfaces, although this is a matter of choice.

In order to secure my stacking iron and reinforcement in place I provide the horizontal top 4 with a plurality of openings 14

to receive suitable fastening devices, such as nails 15. These openings may be of any desired number but in this embodiment I have illustrated them as being four in number and registering with two of them, I provide openings 16 in the lugs 7 and 8 whereby certain of the nails 15 may be supplied of any sufficient length to pass through both openings 14 and 16 to securely anchor the iron in place. These nails are preferably countersunk at their heads, as shown, to provide a smooth upper surface on which the next crate or box may rest.

From the above description it will be seen that I have provided a novel and improved box or crate having a reinforcement for a corner thereof which may be easily stamped out of one sheet of material and which, when applied, may be fastened in place by a few nails and without the use of any more complicated fastening means, such as rivets or bolts.

The aligned apertures 14 and 16 provide means for securely anchoring the device in position and it can not become loose without breaking the crate or box. The horizontal top 4 provides an increased wearing surface for the box or crate which is to be placed on top thereof and the sides 10 and 11 of the projection will engage within the corner of the next crate or box to hold it in position. The bottom of the

next box on top may be provided with a complementary iron or may be left plain, as desired. Of course, it is evident that the projection designed to engage the bottom of another box may be omitted if it is desired to use my invention with other types of boxes or crates and the remaining structure forms a most efficient and satisfactory reinforcement and protection for the corner.

While I have shown and described my

invention as forming a combined stacking iron and corner reinforcement, it is to be understood that it is not limited to use at the corner of a box or crate but may find 5 utility in other places to which it may be adapted. I am aware that changes in the form, construction and arrangement of parts may be made without departing from the spirit and without sacrificing the advantages of the invention and I reserve the 10 right to make all such changes as fairly fall within the scope of the following claims.

I claim:—

15. 1. A device of the class described comprising a horizontal top adapted to contact with the top edge of a box or crate, and a vertical side adapted to contact with a side of said box or crate, said side terminating in 20 a bent-in lug adapted to engage in a slot in said box.
2. A device of the class described comprising a horizontal top adapted to contact with the top edge of a box or crate, and a 25 vertical side adapted to contact with a side of said box or crate, said side terminating in a bent-in lug adapted to engage in a slot in said box, said top and said lug being provided with apertures to receive fastening 30 means.
3. A device of the class described comprising a horizontal top adapted to contact with the top edge of a box or crate, and a

vertical side adapted to contact with a side of said box or crate, said side terminating in 35 a bent-in lug adapted to engage in a slot in said box, said top and said lug being provided with apertures to receive fastening means, certain of the apertures in said top and bottom being aligned.

4. A device of the class described having vertical sides arranged at right angles to each other, a horizontal top connecting the top edge of said sides, a projection above 40 said top for the purpose set forth, the lower edges of said vertical sides being provided with bent-in lugs, and aligned apertures in said top and said lugs to receive fastening means.

5. In combination, a box having slots adjacent a corner thereof, a stacking iron adapted to cover said corner and having bent-in lugs entering said slots and a top covering the upper edges of said corner, and 45 fastening means passing through said top and said lugs.

6. In combination, a box having a slot in a wall thereof adjacent a corner, a stacking iron disposed on the top edge of said box adjacent the corner thereof and having a 50 bent-in lug entering said slot and having a top overlying the edge of said box, and fastening means passing through apertures in said top and in said lug thereby securing said iron to said box.

ROBERT STODDARD.
